William Gale. Patented December 7th 1826.

The Schedule referred to in these Letters Patent
is making part of the specification, as follows.
Invention in the words of the said William Gale
himself of his improvements in the manufacture
of silver spoons, and forks, with or without ornaments.

To all persons to whom these presents shall come,
William Gale of the City, County & State of New-
York, Silver Smith, Doct's greeting: Be it known
that the said William Gale have invented a mode
and applied to use in making and manufacturing
in making or manufacturing silver spoons and
silver forks, which improvement is in the words
of his patent following, to wit: The manufacture consists
of two flat rollers of iron & a half inches in circum-
ference and a half inches in long they these
rollers are placed one above the other in the same
manner that rollers used by Silver Smiths generally
are; they are usually denominates rolling mills,
see letters A and B on figures 1 of the drawing anno-

tionnally on these rollers is a die sunk one
for the upper & one for the under side of the
spoon & fork see letters C and D on figure 1 of
the drawing annexed. These dies are sunk in the
rollers so that ornaments in bass relief are made
the whole length of the handle as the fork & spoon
is represented in figure 2 & 3. Another die is

such as shown in letter B, on one of the rollers only to make a spoon perfectly plain. These rollers are placed in strong fiber and brass frames, and work in the same manner with common rollers as represented in figures 1. In the top of the frame, scales are placed to regulate the rollers. These rollers may be turned by hand, horse, or steam power; the one now used by me is turned by hand with crooked - The silver must be prepared to the suitable size & thickness, and applied to the side of the rollers so as to come in contact with & be received by the ends of the dies in their revolution. It is received on the other side in the flat form of the spoon or fork.

The ornaments are perfectly formed in brass relief - The spoon then requires only to be shaped, the bowl to be formed and fine polished. - The silver for the fork must be prepared in the same way and applied in the same manner, and is in this way perfectly made, requiring only to be shaped & fine polished. - I intend to apply this principle or improvement to the making of all kinds of silver spoons & forks, to any vessel every form and pattern...
